UNITED STATES PATENT OFFICE.

LARS H. LARSON, OF HARTLAND, MINNESOTA.

CORN-PLANTER.

SPECIFICATION forming part of Letters Patent No. 605,608, dated June 14, 1898.

Application filed August 31, 1897. Serial No. 650,133. (No model.)

To all whom it may concern:

Be it known that I, LARS H. LARSON, of Hartland, in the county of Freeborn and State of Minnesota, have invented certain new and useful Improvements in Corn-Planters; and I do hereby declare the following to be a full, clear, and exact description of the invention, such as will enable others skilled in the art to which it appertains to make and use the same.

10 This invention relates to corn-planters; and it consists, essentially, of devices for operating markers of a specific form of construction.

The invention further consists of the details of construction and arrangement of the 15 several parts which will be more fully herein-after described and claimed.

The object of the invention is to provide positively - acting markers or check - rows wherein the parts can be readily shifted to operate on either one side or the other by a simple and effective arrangement of the mechanism which is controlled by the driver without requiring dismounting from the machine.

In the accompanying drawings, Figure 1 is 25 a rear view of a corn-planter embodying the invention. Fig. 2 is a cross - sectional view on the line $x-x$, Fig. 4. Fig. 3 is a cross-sectional view on the line $y-y$, Fig. 4. Fig. 4 is a top plan view of the planter broken away 30 in part. Fig. 5 is a longitudinal vertical section on the line $z-z$, Fig. 4. Fig. 6 is a section on the line $w-w$, Fig. 4, showing one of the markers or check-rows on an enlarged scale. Fig. 7 is a detail sectional view of the 35 seedbox, a part of the slide, and one of the boots. Fig. 8 is a top sectional view of one of the seedboxes. Fig. 9 is a detail view of one of the gears. Fig. 10 is a detail view of a surrounding guard for one of the shifting 40 levers.

Referring to the drawings, wherein similar numerals of reference are employed to indicate corresponding parts in the several views, the numeral 1 designates a frame of suitable 45 dimension and having cross - supports and braces arranged at various points, which will be hereinafter referred to, where necessary, and also provided with ground-wheels 2 on an elongated axle 3, extending entirely through 50 the machine from end to end. Secured on the axle 3 inside of the ends of the frame 1 are sprocket-wheels 4 or analogous devices

having inner clutch-rims 5, adapted to be engaged by adjustable clutch-sleeves 6, and surrounding the shaft are coiled springs 6^a, which 55 tend to normally throw said sleeves into engagement with the clutch-rims. The said clutch-sleeves 6 are movable on the axle 3 and have attached thereto rods 7, which are connected at their inner ends to a turn-head 8 on 60 the outer end of a counter-shaft 9, projecting through to the rear of the machine and supplied with an operating-handle or grip 10.

Through the medium of the rod 7 and the counter-shaft 9 the clutch-sleeves 6 are held 65 out of engagement with the clutch-rims 5 when the machine is not in use. It will be understood that the said sprocket-wheels 4 run loosely on the axle 3 and that the said clutch-sleeves 6 are feathered, and by this 70 means the several parts are thrown into operation or disconnected when not in use. On the rear portion of the frame 1 are uprights 11, in which the ends of a shaft 12 have bearing, said shaft being square in the main and 75 rounded only where engaged by parts loosely mounted thereon, which will now be set forth. On the said shaft are loosely mounted clutch-disks 13 of any preferred form of construction, and integrally formed therewith are 80 small sprocket-wheels or analogous devices 14. The said sprocket-wheels 14 are engaged by belts 15, running from the sprocket-wheels 4, and on the square portions of the said shaft 12 are also adjustably mounted clutch- 85 heads 16, to which are attached the ends of a shifting rod 17, having secured thereto a shifting lever 18, fulcrumed at its outer end on an upright 19, having projections to interlock with a rack 20, adjacently situated 90 and provided with a surrounding guard 21. The rear end of the shifting lever projects within convenient reaching distance of a driver's seat 22 and is operated to throw the opposite clutch-heads 16 in and out of connection with the clutch-disks 13. On the 95 said shaft 12 is keyed a gear 23, having bevel-teeth 24 and spur-teeth 25. The teeth 24 project outwardly a less distance than the teeth 25 and are engaged by a pinion 26, carried on the end of a turn-rod 27, having a handle 28 and which is movably mounted in a guide 29, supported by a standard 30. This pinion 26 is caused to engage the teeth

24 to primarily arrange one or the other of the markers, which will be hereinafter set forth, to properly position the same when starting to work with the machine. After 5 this adjustment is secured the pinion 26 is drawn back and disengaged from the teeth 24.

In advance of the shaft 12 is an intermediate controlling-shaft 31, which through the interposition of mechanisms operated thereby 10 actuates the slides in the seedboxes and lowers the markers. On the said shaft 31 is keyed a pinion 32, which meshes with the gear-teeth 25 of the wheel 23. On the outer ends of the shaft 31 disks 33 are secured, and 15 thereto are eccentrically attached pitmen 34, having their outer ends connected to the inner ends of crank-shafts 35, bearing in supports 36, extending upwardly from a part of the frame. The cranks of the shaft 35 are 20 arranged in reverse planes, and to the outermost ends of each is attached a connecting rod or bar 37, projecting downwardly and movably attached to the upper portion of a follower 38, which has openings 39 extending through opposite sides thereof, in which are movably mounted posts 40, projecting upwardly from a marker 41. The said follower 38 has its opposite ends seated in guides 42, depending from opposite portions of the 25 frame 1, at the end of the latter, and held rigid by braces 43, attached to the lower ends of the said guides and also to adjacent portions of the said frame. Surrounding the posts 40 are coiled springs 44, which bear against the 30 followers 38 at their upper ends and on washers 45, held on the upper edges of the markers 41. Seedboxes 46 are located on the frame outside of the pitmen 34, and coacting therewith is a continuous slide 47, and thereto is 35 movably attached a pitman 48, having its opposite end eccentrically connected with the outer portion of a crank 49, keyed to a small counter-shaft 50, having on its opposite end a similar gear 51. Meshing with the gear 51 40 is a larger beveled gear 52, keyed to a shaft 53, which has on its opposite end a ratchet-wheel 54. The shafts 50 and 53 are supported by a suitable standard rising from a platform 55. At the rear central portion of the frame 45 and engaging the ratchet-wheel 54 is a pawl 56, having a keeper 57 thereon, which tends to hold the pawl in engagement with the ratchet-wheel, and at the rear the said keeper has a vertically-disposed operating-support 55 58, which is adapted to be engaged by an arm 59, mounted on the shaft 31. To the said support 58, at the lower portion thereof, is attached the front end of a retracting-rod 60, seated in guides 61, and between the rear-most guide and the rear end of the said rod 6c is a coiled spring 62.

Below the seedboxes 46 are boots 63, which communicate with runners 64, braced at their front ends by a cross-rod 65, connected to 65 hangers 66. Also attached to the markers 41 are stay-rods 67, having their outer ends movably connected to pins 68, extending out-

wardly from hangers 69, depending from the front portion of the machine. To the front bar of the frame are also secured suitable 70 clips 70 for the attachment of a pole, and on the platform 55 is a line-holding support 71, consisting of an upwardly-extending arm with an angular bent looped end 72, through which the lines or driving-reins may be placed and 75 conveniently held while manipulating the machine. The rear of the frame has trailers or coverers 73 attached thereto of any preferred form of construction.

The sprocket-wheels 4 and 14 may be replaced by grooved wheels engaged by a belt, and to accommodate this arrangement adjustable belt-tighteners 74 are positioned on the inner portions of the ends of the frame and comprise small pulleys 75, carried by adjustable spindles 76. This change of driving mechanism will be readily understood by those skilled in the art.

In operation the marker 41 on either end is lowered to an engaging position with the ground by the turn-rod 27, the latter being adjusted to cause the pinion 26 to engage the gear-teeth 24 on the gear 23. The shifting rod 17 is then operated to throw the proper clutch-head 16 in connection with the clutch-disk 13, and by this means the shaft 12 is revolved and rotates the gear 23. The teeth 25, which extend only partially around the gear 23, strike the pinion 32 and operate the shaft 31 and actuate the disks 33, which in turn operate the pitmen 34 and the crank-shafts 35 to reciprocate in a vertical plane the markers 41. The yielding attachment of the said markers through the springs in engagement with the posts thereof prevent breakage of the said markers as they are brought into contact with the ground or in striking obstructions. In the operation of the shaft 31 the arm 59 thereof actuates the seed-slide 47 through the pitman 48, operated by the mechanism set forth, and the said slide and marker mechanism are so timed that when properly started, in connection with the check made by the planter, the corn will be dropped in the checks previously made from the opposite seedboxes.

It will be understood that the clutch-sleeves 6 will be primarily thrown into engagement with the clutch-rims of the wheels 4, and when it is desired to stop the machine the said 120 clutch-sleeves are disconnected from the clutch-rim and the several parts thereby caused to cease their movements. If the markers 41 should be down at the time the machine stops, they can be raised by the turn-rod 27 and pinion 26 in a manner similar to the primary arrangement of the said markers. The gear-teeth 25, extending only partially around the gear 23, cause an intermittent operation of the shaft 35, which, however, is 125 rapid enough to attain the desired result.

It is obviously apparent that many minor changes in the details of construction and arrangement of the several parts might be made

and substituted for those shown and described without in the least departing from the nature or spirit of the invention.

Having thus described the invention, what is claimed as new is—

1. In a corn-planter, the combination of a shaft having clutch-heads thereon, disks with which the said clutch-heads engage, means for operating the said disks, another shaft operated by the aforesaid shaft and having disks on the ends thereof, crank-shafts attached to said disks, and vertically-reciprocating markers connected to and operated by the said crank-shafts, substantially as and for the purposes specified.

2. In a corn-planter, the combination of a controlling-shaft provided with an arm, a pawl supported by a slide-rod, a keeper engaging said pawl, a ratchet-wheel, a seed-slide, gearing in connection with said ratchet-wheel and seed-slide, and seedboxes with which said slide coacts, substantially as and for the purposes specified.

3. In a corn-planter, the combination of a drive-shaft, another shaft in connection therewith having a gear thereon, a controlling-shaft engaging said gear, crank-shafts connected to said controlling-shaft, vertically-

reciprocating markers operated by the said crank-shafts, and an adjustable turn-rod carrying a pinion adapted to engage the said gear, and to adjust the said markers, substantially as and for the purposes specified.

4. In a corn-planter, the combination of a shaft having a gear thereon, means for operating said shaft, a controlling-shaft carrying the pinion adapted to mesh with said gear, and provided with an arm, crank-shafts connected to said controlling-shaft, vertically-reciprocating markers attached to and operated by said crank-shafts, a yielding pawl adapted to be engaged by the arm of the controlling-shaft, a ratchet-wheel and gearing actuated by the said yielding pawl, a feed-slide connected to the gearing actuated by the pawl, seedboxes with which the said slide engages, and means for throwing the several parts in and out of gear, substantially as and for the purposes specified.

In testimony whereof I have signed this specification in the presence of two subscribing witnesses.

L. H. LARSON.
